(57) **CLAIM**

The ornamental design for a fender flare, as shown and described.

DESCRIPTION

FIG. 1 is a front perspective view of a golf cart showing our new design of a fender flare on a first side and a second side of the golf cart;

FIG. 2 is another front perspective view of the golf cart of FIG. 1 showing the fender flare on the first and second sides of the golf cart;

FIG. 3 is a side view of the first side of the golf cart of FIG. 1 showing the fender flare;

FIG. 4 is a side view of the second side of the golf cart of FIG. 1 showing the fender flare;

FIG. 5 is a front view of the golf cart of FIG. 1 showing the fender flare on the first and second sides of the golf cart;

FIG. 6 is a rear view of the golf cart of FIG. 1; and,

FIG. 7 is a top view of the golf cart of FIG. 1 showing the fender flare on the first and second sides of the golf cart. In FIGS. 1-7, broken lines indicate environmental structure that forms no part of the claimed design.

1 Claim, 7 Drawing Sheets
